(57) **CLAIM**

The ornamental design for a display screen or portion thereof with an icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a first embodiment of a display screen or portion thereof with an icon showing my new design;

FIG. 2 is a front view of another embodiment of a display screen or portion thereof with an icon showing my new design; and,

FIG. 3 is a front view of another embodiment of a display screen or portion thereof with an icon showing my new design.

The broken lines represent the display screen and form no part of the claimed design.

1 Claim, 3 Drawing Sheets
